DOOR HANGER FOR BOX CARS OR THE LIKE

Deeny Morris Bennett, Waycross, Ga.

Application June 1, 1932. Serial No. 614,784

4 Claims. (Cl. 16—97)

This invention relates to improvements in hangers for doors, particularly the doors of box cars and relates especially to wheeled hangers.

The primary object of the present invention is to provide a hanger having a novel means of mounting a supporting wheel which facilitates the rapid replacement thereof when necessary. Another object of the invention is to provide a door hanger having a supporting roller mounted upon a pivot pin which pin is of a character to be turned to present a new wear surface after one side thereof has become worn to such an extent that the ready operation of the door supported by the hanger is affected. 15 A still further object of the invention is to provide a door hanger having a plate portion which is attached to the door and a roller carrying portion which is detachably connected with the plate and which can be readily removed from the plate when repair or replacement of the rollers or their supporting trunnions is necessary, without removing the entire hanger from the door.

The invention will be best understood from 25 a consideration of the following detailed description taken in connection with the accompanying drawing forming part of this specification, with the understanding, however, that the invention is not confined to any strict conformity with 30 the showing of the drawing but may be changed or modified so long as such changes or modifications mark no material departure from the salient features of the invention as expressed in the appended claims.

35 In the drawing:—

Figure 1 is a view in elevation of the inner side of the hanger embodying the present invention;

40 Figure 2 is a vertical sectional view through the hanger and associate door parts to which the same is shown attached;

Figure 3 is a sectional view taken on the line 3—3 of Figure 1;

45 Figure 4 is a view in edge elevation of a form of the hanger designed for use upon the bottom of a door.

Referring now more particularly to the drawing wherein like numerals of reference indicate 50 corresponding parts throughout the several views, the numeral 1 indicates a portion of a door structure to which the present hanger is shown attached, a trackway in the form of a channel bar being indicated by the numeral 2.

55 This is only one of the several forms of trackways which are at present in use and, therefore, it will be understood that the use of the invention is not to be confined to a track of this character for an ordinary L-shaped or angle bar 60 may be employed or any other type of track

having a flange upon which the wheels of the hanger may run.

The hanger embodying the present invention is indicated as a whole by the numeral 3 and as shown comprises the plate portion 4 having a reduced top extension 5 which is off-set from the plane of the plate and is of slightly increased thickness, as illustrated. This off-set top portion has a dove-tail groove 6 formed in and transversely of this inner face and the top portion of the plate 4 has a recessed portion 7 transversely of its upper face in which is mounted one side of an angle guard which is indicated generally by the numeral 8. This guard 8 has the two spaced parallel side portions 9 and 10 and the right angularly disposed intermediate portion 11 connecting them, which intermediate portion is horizontally positioned when the hanger is attached to the door body 1. The portion 11 of the angle guard positions upon the top edge of the 70 door, as illustrated.

75 Disposed against the inner face of the head portion 5 of the hanger is the elongated flat head block 12, the ends of which extend beyond the side edges of the portion 5. The face of the head block 12 which abuts the portion 5 of the hanger carries a cleat 13, the longitudinal edges of which are beveled or under-cut so that the cleat may be inserted into the dove-tail slot 6 to effect the securing connection of the head 80 block with the upper part of the plate.

85 Each end of the head block 12 is bifurcated to form the longitudinally extending slot 14 and the portions at each side of the slot are cut away from the bottom edges thereof to form the 90 downwardly opening notches 15.

95 These notches are of polygonal outline, being preferably rectangular.

Positioned in each slot 14 is a wheel 16 which is provided with a central aperture 17 through 100 which extends the round axle 18. A portion of each end of the axle 18 is of the same polygonal outline as the notches 15, as indicated at 19 and in the present case these ends or trunnion portions of the axles are square and designed to 105 snugly fit in the notches 15 when the wheels 16 are in place.

110 The head block 12 has a transverse threaded passage 20 therethrough and this passage at the inner face of the block is counter-bored as at 21, and through this passage is passed a bolt 22, the head of the bolt positioning against the outer side of the block, while the shank engages the threads in the bore, thus securing the block against displacement.

115 From the foregoing description it will be readily apparent that in the assembly of the present hanger the block is attached to the upper portion of the plate after the axles 18 have been placed in the wheels and the wheels inserted into their 120

respective slots 14 with the squared ends of the axles positioned in the notches 15. The plate 4 may have been previously attached to the door body in which case the cleat 13 will be slipped 5 into the dove-tail groove 6 with the wheels 16 engaging the supporting track 2. The holding bolt 22 may then be placed in position and secured.

Since the notches 15 have their open sides directed downwardly it will be readily apparent that the weight of the door will hold the axles firmly in place and it will also be readily apparent that after the hangers have been in use, and the axles become worn upon the under side, 15 the head block may be removed and the axles taken out and given a quarter turn so as to bring a new or unworn surface into position for use. This operation may be continued until the axle has been turned three times after its initial in- 20 stallation. It will thus be apparent that with a hanger of this character the wheel supporting axles may be used for a considerably longer period than in hangers of other types and it will also be readily apparent that the changing of 25 the axles or replacement of the wheels may be accomplished easily and quickly and without the necessity of having to remove the entire hanger from the door.

In Figure 4 there is illustrated a slight modification of the hanger structure just described, 30 which modification is designed for use upon the bottom of the door. This modified form of hanger, or bottom hanger, is indicated generally by the numeral 24 and as shown comprises a plate portion 25 with which is integrally formed a channel or frame portion 26 which has its open side directed inwardly toward the door 27 when the plate 25 is secured to the outer face thereof.

40 The channel portion 26 of the bracket 24 has the inner face of its vertical side 28 provided with a dove-tail groove 29 in which is slidably engaged the cleat 30 which is carried by a roller block 31.

45 This roller block 31 is slotted at its ends like the block 12 of the top hanger as indicated at 32 and in each of these slots is mounted a roller 33 upon an axle 34. The ends of this axle 34 are of polygonal cross sectional design like the 50 axles 18, and these engage in suitable notches formed in the bottom edges of the portions of the block 31 which border the slots 32. As will, of course, be readily apparent the axles 34 can only be detached from the roller block 31 by 55 being moved downwardly and since the brackets are placed in such a manner that the rollers rest upon an underlying track 35, the weight of the door maintains the rollers and the axles in place.

60 The block 31 is further secured to the bracket portion 26 of the hanger by a bolt 36 which passes therethrough and through the vertical part 28 of the hanger, in substantially the same manner as the bolt 22 of the top hanger struc- 65 ture.

From the foregoing description it will be readily apparent that both types of hangers herein described are so designed that the rollers and carriers therefor may be easily and quickly removed from place for replacement or repair without having to detach the entire bracket from the door and as has been previously explained

the axles may be readily shifted or turned after becoming worn at one point, to arrange a new portion in position to take up the wear and in this manner the life of the entire hanger will be greatly prolonged.

Having thus described the invention, what is claimed is:—

1. A door hanger comprising a wheel block, an axle disposed transversely of and carried by the block, means coupling the axle with the block whereby the axle may be turned to and held in any one of several positions of oscillation about its long axis, a wheel mounted upon the axle, and means for securing the block to a door body in position for the wheel to rest upon the top of a supporting track.

2. A door hanger comprising a plate body designed to be secured to a door and having a head portion arranged in off-set parallel relation thereto, said head portion having a dove-tail groove formed across its inner face, an elongated wheel block of a length greater than the width of said head and having a recess formed in each end and further having transverse notches across its lower edge, a cleat carried by the wheel block for slidable engagement in said groove, a wheel disposed in each recess, and an axle extending through each wheel and having each end engaged in an adjacent notch.

3. A sliding door hanger, comprising a plate designed to be secured to a face of a door and having an integral off-set parallel head portion designed to extend beyond the adjacent edge of the door and off-set from the adjacent face thereof, the inner face of said head being provided with a transverse dove-tail channel, an elongated block disposed to extend across the said face of the head and having downwardly opening recesses in each end thereof, a cleat formed longitudinally of the central portion of one side face of the block, said cleat being of dove-tail cross section to slidably position in said channel, wheel axles disposed transversely of each of the recesses of the block, a wheel in each recess and rotatably mounted on the axle 115 therein, and means for securing said block against longitudinal movement upon said head.

4. A sliding door hanger, comprising a plate designed to be secured to a face of a door and having an integral off-set parallel head portion designed to extend beyond the adjacent edge of the door and off-set from the adjacent face thereof, the inner face of said head being provided with a transverse dove-tail channel, an elongated block disposed to extend across the 120 said face of the head and having downwardly opening recesses in each end thereof, a cleat formed longitudinally of the central portion of one side face of the block, said cleat being of dove-tail cross section to slidably position in said channel, wheel axles disposed transversely of each of the recesses of the block, a wheel in each recess and rotatably mounted on the axle 125 therein, and means for securing said block against longitudinal movement upon said head, said off-set head having the portion connecting it with the plate forming a substantially right angular shoulder and said block having a longitudinal edge in abutting relation with said shoulder.
